US00D886123S

(12) **United States Design Patent** (10) **Patent No.:** **US D886,123 S**
De Runa et al. (45) **Date of Patent:** **** Jun. 2, 2020**

(54) **DISPLAY SCREEN OR PORTION THEREOF INCLUDING A GRAPHICAL USER INTERFACE**

(71) Applicant: **SAMSUNG ELECTRONICS CO., LTD.**, Suwon-si (KR)

(72) Inventors: **Charles Jason De Runa**, Mountain View, CA (US); **Xiaoqing Jing**, Mountain View, CA (US); **Gerald Taa**, Mountain View, CA (US)

(73) Assignee: **SAMSUNG ELECTRONICS CO., LTD.**, Suwon-si (KR)

(**) Term: **15 Years**

(21) Appl. No.: **29/648,101**

(22) Filed: **May 18, 2018**

Related U.S. Application Data

(63) Continuation of application No. 29/587,461, filed on Dec. 13, 2016, now abandoned.
